(57) **CLAIM**

The ornamental design for a mannequin as shown and described.

DESCRIPTION

FIG. 1 is a front view of a mannequin according to the claimed design.

FIG. 2 is a rear view of the mannequin.

FIG. 3 is a left side view of the mannequin.

FIG. 4 is a right side view of the mannequin.

FIG. 5 is a top view of the mannequin.

FIG. 6 is a bottom view of the mannequin.

FIG. 7 is a front-right side perspective view of the mannequin.

FIG. 8 is a bottom-rear perspective view of the mannequin; and,

FIG. 9 is a top-right side perspective view of the mannequin. The dot-dot-dash broken lines in the drawings define the bounds of the claimed design and form no part thereof. The other broken lines in the drawings illustrate portions of the mannequin that form no part of the claimed design.

1 Claim, 9 Drawing Sheets
